UNITED STATES PATENT OFFICE.

HORACE H. DOLL, OF PHILADELPHIA, PENNSYLVANIA.

AUTOMATIC SWITCH.

SPECIFICATION forming part of Letters Patent No. 733,822, dated July 14, 1903.

Application filed September 29, 1902. Serial No. 125,270. (No model.)

To all whom it may concern:

Be it known that I, HORACE H. DOLL, a citizen of the United States, residing at Philadelphia, in the county of Philadelphia and State of Pennsylvania, have invented certain new and useful Improvements in Automatic Switches; and I do declare the following to be a full, clear, and exact description of the invention, such as will enable others skilled in the art to which it appertains to make and use the same.

My invention relates to certain improvements in the railroad-switch described in Patent No. 703,561, dated July 1, 1902, and issued to M. H. Bostian and myself. The switch is of that class designed to be operated from an approaching car and which is locked in position during the travel of the car or cars over the switch and then automatically returned to the original position after the car or cars have left the same.

In the accompanying drawings, Figure 1 is a plan view of an automatic switch constructed and arranged in accordance with my invention. Fig. 2 is a side elevation of a portion of the same. Fig. 3 is an enlarged detail view of the hand-lever, the T-shaped lever, and its connections which embody my improvements. The dotted lines represent the position of the parts when the hand-lever is moved to operate the switch-points without affecting the levers C', C², C³, or C⁴. Fig. 4 is an elevation of a car-truck carrying switch-operating shoes in accordance with the invention.

Referring more particularly to the drawings, the letter A' denotes an open main track, the rails of a side leading to the switch. On the ties at the sides of the rails are secured plates a' a² a³ a⁴, arranged in pairs, the plates a' a² being outside the siding-rails. On these plates, respectively, are pivoted levers C' C² C³ C⁴, having curved faces close to the outer edges of the rails for contact with the switch-ing-shoes B, carried by the trucks C. The trucks C or, as the case may be, the forward end of the engine or the platform of the car are provided with the shoes B, having shanks a, guided in suitable vertical bearings on the cars and normally held in an elevated position by springs a⁵ or any equivalent means, their depression to operative position being

effected by any engine-driver or motorman.

The needle or switch points B' B² are of the usual type, and both are secured to a transverse bar N', the movement of which clears either the main-line or the siding rails. This bar N' is secured at one end to a T-shaped lever K, fulcrumed at the center of its three arms to a base-plate x. The main arm k of this lever is adapted to be engaged by the lower end of a hand-lever J, pivoted to a bracket x' upon the base x. Upon the operation of the lever J the T-shaped lever K will be forced to the dotted-line position, as illustrated in Fig. 3, for a purpose herein-after described. The lever K is also operated upon by a spring k', so as to keep it in the position shown in Fig. 1, the spring being guided by a bolt l, connected to a bracket N upon the base x, said bracket being adjustable on said base-plate to increase or decrease the pressure of the spring.

Extending from the lever C' to the arm k of the lever K are a series of levers and connecting-bars consisting of the pivoted bell-crank lever D', the similar lever F', the rod E', connecting the same, the rod G', connecting one arm of the lever F', and an arm of the pivoted bell-crank lever H', the other arm h of which is provided with a bent end adapted to engage one arm of a pivoted bell-crank lever I', the other arm of which is connected to the arm k by a rod or link I². It will thus be noticed that owing to the arrangement of the levers H' and I', I have a loose connection between the lever K and the lever C', for a purpose herein-after described, while in the Patent No. 703,561 the connection between the two said levers is positive. The arrangement of these levers when the parts are in the normal position, as seen in Fig. 1, is such that when the shoe B on the on-curving car presses against the lever C' the lever K will be moved against the action of the spring L to move the bar N' to open the switch to the siding-rails. The lever C² is connected to the rod G' through the medium of the bell-crank lever D² for a similar purpose as the lever C'.

On the switch-rails the lever C³ is connected to the arm k of the lever K in the following manner: A rod E³ connects the pivoted lever D³, which is engaged by the lever C³, and one arm of the bell-crank lever F³, the other arm

of which has pivoted to it the connecting-rod G², which is provided with a pin g upon its opposite end. The said pin is adapted to engage and slide in the slotted end g² of the connecting-rod I³, which has its opposite end pivoted to the arm h of the lever K. It will thus be seen that owing to this pin-and-slot connection between the rods G² and I³, I have a loose connection between the lever K and the lever C³, while in the before-mentioned patent the connection is positive. The lever C⁴ is connected to the lever K by means of the bell-crank lever F², the lever D⁴, and the connecting-rod E². The operation of these parts when the parts are seen in Fig. 1 is such that when either of the levers C³ or C⁴ is operated the lever K will be operated against the tension of the spring K'.

Owing to the loose connections between the two sets of levers C' C² and C³ C⁴ and the lever K, it will be noticed that either set may be operated independently of the other to move the lever K—that is to say, when a car with its shoe B depressed approaches one or the other of the sets of levers C' C² and C³ C⁴ only that set which the car first approaches will operate, while the other set will remain quiet. When either of the levers C', C², C³, or C⁴ is operated, the lever K will be moved from the position shown in Fig. 1 to change the switch-points B' B² and open communication between the main line and the siding. Owing to these loose connections between the levers C', C², C³, and C⁴ and the lever K, it will be further noted that upon throwing the hand-lever J to the dotted-line position, as seen in Fig. 3, the switch-points may be thrown without affecting the levers C', C², C³, or C⁴, since the free arm of the lever I will move away from the arm h of the lever H' and the hinge will ride up in the slot g² as the link I³ is forced over. When said lever is not in use, it may be swung to a horizontal position, as seen in Fig. 1, and locked under the bracket x³.

The switch-bar N' is secured to or formed integral with a bar N², having its outer end guided in a frame R, provided with openings for the reception of locking-pins s, which may enter into a suitable opening in the bar N² and lock the same to keep the switch either open or closed during the passage of a car or cars. This locking-rail U extends parallel with and outside of the curved rail of the siding from points opposite the levers C' C⁴, its upper edge being a trifle above the level of the load-rail, so that it may be acted upon by the wheels. The rail U has pins or trunnions W, adapted to coact with curved slots w in plates V, secured to permanent bases, and this rail is connected by a lug T, rod O², bell-crank lever P, and rod O' to the one arm of the main operating-lever K, the connection being such that the locking-rail is moved backward or forward at each movement of the switch-lever.

To the lugs V' V² on the locking-rail are

pivoted arms Z' Z², respectively forming universal joints for the attachment of the spring locking-pins s, the movement of the rail withdrawing one or the other of such pins from engagement with the bar N².

The operation of the device is as follows: If the parts be in the normal position, as in Fig. 1, with the main-line rails open, and a car or train approaching on the main line wishes to take the siding or a car or train on the siding wishes to take the main line, the engineer or motorman depresses the shoe B. This shoe then comes into contact with one or the other of the levers of the two pairs C' C² or C³ C⁴ and through the intervening levers previously described operates one set only to move the lever K and switch-bar N' to open the switch to the siding, while the other set remains quiet. This movement also shifts the locking-rail and causes one or the other of the pins s to lock the switch in the position to which it is adjusted. The car or train then enters upon and depresses the locking-rail, holding the same in its locking position until the last wheel of the car or train has left it. The spring K' then acts to cause all the parts to reassume their normal positions, leaving the main line again open for traffic. By means of the hand-lever J the switch-points may be operated by hand and without the operation of any of the levers C', C², C³, or C⁴, as previously described.

The device is admirably adapted for street-railways, and especially electrical railways in rural districts, where single lines are used and cars must pass each other on sidings; but it may be used in any capacity on street, electric, or steam railroads, as desired.

The invention may be modified in a variety of ways, and the number and arrangement of levers and operating devices increased or diminished, and the method of connecting same may be changed without departing from the spirit of the invention.

Having thus described my invention, what I claim as new, and desire to secure by Letters Patent, is—

1. In an automatic switch, the combination with the main and siding rails, switch-points movable between said rails, and a switch-bar connected to the switch-points, of a main operating-lever connected to said bar, two sets of operating-levers arranged alongside the main and siding rails for actuating the main operating-lever respectively from said rails, intermediate power-transmitting levers, a hand-lever, and loose connection between said intermediate levers and the main operating-lever whereby said main operating-lever may be operated from the hand-lever or either of the operating-levers without affecting any of the other operating-levers, substantially as described.

2. In an automatic switch, the combination with the main and siding rails, switch-points movable between said rails, and a switch-bar connected to the switch-points, of a main op-

- erating-lever connected to said bar, two sets of operating-levers arranged alongside the main and siding rails for actuating the main operating-lever respectively from said rails, 5 intermediate power-transmitting levers connected to said two sets of operating-levers, operating-rods connected to the power-transmitting levers, and loose connection between said rods and, the main operating-lever, substantially as described.
3. In an automatic switch, the combination with the main and siding rails, switch-points movable between said rails, and a switch-bar connected to the switch-points, of a main operating-lever connected to said bar, two sets of operating-levers arranged alongside the main and siding rails for actuating the main operating-lever respectively from said rails, intermediate power-transmitting levers connected to said two sets of operating-levers, operating-rods connected to the power-transmitting levers, and loose connections between said rods and the main operating-lever, and a pivoted hand-lever free from connection 20 with but adapted to be engaged with the main operating-lever to throw the switch without affecting the other levers, substantially as described.
4. In an automatic switch, the combination with the main and siding rails, switch-points movable between said rails, and a switch-bar connected to the switch-points, of a main operating-lever connected to said bar, two sets of operating-levers arranged alongside the main and siding rails for actuating the main operating-lever respectively from said rails, an intermediate power-transmitting lever connected to each set of operating-levers, operating-rods connected to the power-transmitting levers, and loose connection between 25

the rods and the main operating-lever, the loose connections of one rod consisting of a pin upon the rod engaging a slotted link connected to the main lever, and that of the other rod consisting of a pair of levers having engaging portions, one of said levers being pivoted to the rod and the other to the main lever, substantially as described. 45

5. In an automatic switch, the combination with the main and siding rails, switch-points movable between said rails, and a switch-bar connected to the switch-points, of a main operating lever connected to said bar, two sets of operating-levers arranged alongside the main and siding rails for actuating the main operating-lever respectively from said rails, an intermediate power-transmitting lever connected to each set of operating-levers, operating-rods connected to the power-transmitting levers, and loose connections between 50 the rods and the main operating-lever, the loose connection of one rod consisting of a pin upon the rod engaging a slotted link connected to the main lever, and that of the other rod consisting of a pair of levers having engaging portions, one of said levers being pivoted to the rod and the other to the main lever, and a pivoted hand-lever free from connection with but adapted to be engaged with the main operating-lever to throw 55 the switch without affecting the other levers, substantially as described. 60

In testimony whereof I have hereunto set my hand in presence of two subscribing witnesses.
